UNITED STATES PATENT OFFICE

GEORGE F. MATTESON, OF ROCKYHILL, CONNECTICUT, ASSIGNOR TO THE F. B. SHUSTER COMPANY, OF NEW HAVEN, CONNECTICUT, A CORPORATION OF CONNECTICUT

STRIP STRAIGHTENING AND CUTTING MACHINE

Application filed September 28, 1928. Serial No. 308,977.

My invention relates to the class of machines employed for straightening strips of metal and for cutting said strips into predetermined lengths, and an object of my invention, among others, is the production of a machine of this class that shall be simple in construction and particularly simple and efficient in operation.

One form of machine embodying my invention and in the construction and use of which the objects herein set out, as well as others, may be attained, is illustrated in the accompanying drawings, in which—

Figure 1 is a view in side elevation of a machine embodying my invention.

Figure 2 is an end view of the same.

Figure 3 is a detail view in cross section on a plane denoted by the dotted line 3—3 of Figure 1.

Figure 4 is a detail view illustrating the construction and operation of the cutting and stamping mechanism.

Figure 5 is a similar view of the cutter frame and contained mechanism but looking in a direction at right angles from the point of view of Figure 4.

Figure 6 is a detail view in cross section on a plane denoted by the dotted line 6—6 of Figure 4.

Figure 7 is a detail view of a fragment of the pulley showing the means for clamping the cable thereto.

Figure 8 is a detail view in cross section on a plane denoted by the dotted line 8—8 of Figure 7.

In the accompanying drawings the numeral 5 denotes the table of my improved machine that may be supported in any suitable manner, as on standards 6 located at or near each end of the machine, there being such suitable number of standards as may be desired. A straightener 7 is located at one end of the table, this straightener being of any well known type and for which reason a detailed illustration and description thereof are omitted herein.

My improved machine contemplates a structure in which a maximum amount of movement of a strip at each operation may be obtained as compared with prior devices

while maintaining the parts for effecting such movement within practical limits as to size. This is accomplished by means of a drawer 8 slidably mounted upon guides 9 projecting from opposite sides of a support 10 secured to and rising from the table 5, and as shown in Figures 1 and 3 of the drawings, the base 11 of the drawer having suitably formed grooves to receive said guides in a manner that will be readily understood.

A drawer actuator in the form of a cable 12 is secured in any suitable manner by its opposite ends to the drawer 8, one of these attachments preferably being adjustable by means of which the tension of the actuator may be regulated. This actuator passes around guide sheaves 13 located at opposite ends of the support 10, said actuator thus in effect being an endless member. One of its lengths, the lower one as shown herein, intermediate its ends, passes in contact with or around a feed pulley 14 having a groove to receive the actuator 12.

The pulley 14 has an oscillating movement imparted by means of a rack 15 slidably mounted in a box 16 on a support 17 projecting laterally from a leg 4. This rack meshes with a pinion 18 mounted on a stud projecting from the side of said leg which is located intermediate the standards 6, and as shown in Figure 1 of the drawings. This stud is supported at its outer end by a bracket 35 secured to the side of the table 5 and projecting downwardly therefrom. The rack 15 has a pitman comprising a connecting bar 19 pivotally attached at one end to the rack and at its opposite end to a stud 53 on an adjustable block operated by a screw threaded rod 20. Said rod at its end opposite the bar 19 is engaged with a block 21 secured in a slot 22 in the side of a feed actuating disc 23 secured to a shaft 36 rotatably mounted as in a bracket 52 extending from the under side of the table 5.

A gear 37 on shaft 36 meshes with a driving pinion 24 secured to the driving shaft 25 mounted in a bearing on the table 5, and as shown in Figure 2 of the drawings. A driving pulley 26 is secured to the shaft 100.

25 as a means for driving the machine, said pulley being adapted to receive a belt from a motor or other suitable source of power.

A gripper of any well known type and 5 embodying a gripper jaw 27 is carried by the drawer 8, this gripper being of that type whereby when the drawer is moved forward it will grip and hold a strip of stock 28, and when moved in the opposite direction 10 said jaw will be automatically released from the strip and permitted to slide freely therealong. This drawer comprising a gripper is in fact a feeding device and operates not only to feed the stock to the cutting 15 or other mechanism, but also to aid the movement of the stock through the straightener when the latter is used.

It will be observed that this machine embodies means whereby the drawer 8 through 20 the actuator 12 may have a maximum range of movement imparted by simple mechanism, the members of which are extremely limited in size. In the arrangement herein shown a wide range of movement is obtainable and by simply changing the gear mechanism connected with the rack 15 to a very 25 limited extent a much wider range of movement may be obtained.

My improved mechanism embodies a cutter 30 for producing strips of a predetermined length from the stock 28, this length, however, being governed by the feed device hereinbefore described. The cutter is timed to operate during the period in 35 which the drawer is moving backwardly to the point for beginning the feed of a strip of stock. The time of operation of the cutter during this period is automatically determined by reason of its connection with 40 the feeding mechanism, such connection embodying a cutter operating gear 29 mounted in bearings on a cutter frame 30 secured to and rising from the table 5. This gear 29 meshes with the pinion 24 and is driven 45 thereby. A crank 31 is carried by a shaft 32 on which the gear 29 is mounted, this crank operating a connecting bar 33, the lower end of which is pivotally attached to a carrier 34 mounted in any suitable manner 50 to act upon the strip of stock 28 and sever it into lengths, by means of a cutter to be hereinafter described.

It will be noted that the gears 37 and 29 55 are of the same size and that each therefore completes its rotation at the same time as the other. The movement of the drawer 8 to feed the stock and its reverse movement will take place during one complete rotation of the gear 37 and consequently at the same 60 time one complete rotation of the gear 29 will effect an operation of the cutter during return movement of the drawer 8 no matter what the position of the block 21 to determine the length of the stock to be cut.

65 A stamping device is arranged for stamp-

ing each strip of stock or material with any suitable character or characters and this stamping device is so connected with the shaft 32 as to operate during each complete rotation of the gear 29. The parts are so 70 arranged that the stamp will make contact with the strip 28 at the time of return movement of the drawer 8, and the stamp, therefore, acts to prevent the drawer 8 from moving the strip of stock backwardly and the 75 latter is, therefore, maintained in the position to which it is drawn by the feed.

In the structure herein shown, a stamping cam 38 is secured to the shaft 32 for operation of a bell crank lever, comprising an 80 arm 39, a rock shaft 40, and a plunger operating arm 41, said arms being secured to the rock shaft at opposite ends thereof, and as shown in Figure 5 of the drawings. An adjusting screw in the arm 41 operates 85 against the end of a stamping plunger 42, mounted for longitudinal movement in a boss 43, on the frame 30. The plunger is forced upwardly as by means of a spring, shown in dotted lines Figure 4 and at its 90 lower end thrusts against a rocker 44, pivotally mounted at the lower end of the frame 30 and having a stamp 45 adapted to be forced against the stock 28 to make an impression thereon. The cam 38 is formed to maintain the stamp 45 in contact with the stock 28 when the drawer 8 is moved backwardly, the stamp therefore acting to hold the stock against backward movement at this time and as herein before described. In the 95 particular form of cutting mechanism as herein shown, the crank 31 projects from a crank disk 46 and the carrier 34 has an inclined opening in which a cutter 47 is adjustably secured as by means of a screw 48. 100 This cutter operates in connection with a cutting die 49 secured in an opening in the lower end of the frame 30, and as shown in Figs. 4 and 5 of the drawings.

The actuator or cable 12 is secured to the 105 pulley 14 as by means of a clamp 50 herein shown in the form of a hook to receive the cable, said hook being held in place by a clamp nut 51, as shown in Fig. 8 of the drawings. In the preferred form of construction, as shown in Figure 7, a recess is 110 formed in the periphery of the pulley 14 into which the cable is drawn by the clamp 50. The cable may be engaged with only a portion of the periphery of the pulley 14 or 115 it may be preferably wrapped one or more times around said pulley. By means of this clamp, the position of the cable on the pulley 14 may be changed and thereby the zone 120 of movement of the drawer 8 may be fixed at any desired location, so that when a length of stock less than that within the 125 maximum limits of the machine is being fed, the drawer may be reciprocated at 130

either end of its zone of movement or intermediate thereof.

In accordance with the provisions of the patent statutes I have described the principles of operation of my invention, together with the device which I now consider to represent the best embodiment thereof; but I desire to have it understood that the device shown is only illustrative and that 10 the invention may be carried out by other means and applied to uses other than those above set out.

I claim:

1. A feeding device for metal working machines, said device including an endless, flexible actuator, guides for said actuator, said actuator including a gripper interposed in the length of said actuator and located and movable in line with and wholly between said guides, means for effecting a reciprocating movement of said actuator, and means on said gripper for automatically gripping a piece of stock when the gripper is moved in one direction but to release said stock when the gripper is moved in an opposite direction.

2. A feeding device for metal working machines, said device including a gripper, a flexible actuator having its opposite ends secured to said gripper to comprise therewith an endless structure, means on said gripper for automatically gripping a piece of stock when the gripper is moved in one direction, but to release said stock when the gripper is moved in an opposite direction, and means for effecting a reciprocating movement of said actuator.

3. A feeding device for metal working machines, said device including a gripper and an endless, flexible actuator secured at its opposite ends to said gripper to comprise an endless structure, one end of the actuator being adjustably secured to the gripper, means on said gripper for automatically gripping a piece of stock when the gripper is moved in one direction, but to release said stock when the gripper is moved in the opposite direction, and means for effecting a reciprocating movement of said actuator.

4. A feeding device for metal working machines, said device including a gripper, a guide upon which said gripper is slidably mounted, an actuator comprising a flexible member having its opposite ends secured to said gripper to comprise an endless member, means on said gripper for automatically gripping a piece of stock when the gripper is moved in one direction, but to release said stock when the gripper is moved in the opposite direction, and means for causing movement of said gripper back and forth.

5. A feeding device for metal working machines, said device including an endless, flexible actuator, guides for said actuator,

said actuator including a gripper interposed in the length of said actuator and located and movable wholly between said guides, means on said gripper to grasp a piece of stock, means for guiding said gripper in movements thereof back and forth, an oscillating actuating member secured to said actuator, and means for oscillating said actuating member.

6. A feeding device for metal working machines, said device including an endless, flexible actuator and said actuator including a gripper interposed in the length of said actuator and movable between guides for the flexible actuator, means for guiding said gripper in movements thereof back and forth, means on said gripper to grasp a piece of stock, a pulley rotatably mounted, means for adjustably securing said actuator to the peripheral edge of said pulley, and means for oscillating said pulley.

7. A feeding device for metal working machines, said device including an endless, flexible actuator and said actuator including a gripper interposed in the length of said actuator, means on said gripper for grasping a piece of stock, a pulley rotatably mounted, means on said pulley for securing said actuator thereto in different positions, and means for oscillating said pulley.

8. A feeding device for metal working machines, said device including an endless, flexible actuator and said actuator including a gripper interposed in the length of said actuator, means on said gripper to grasp a piece of stock, a rotatably mounted pulley to which said actuator is secured, a rack and pinion connection for oscillating said pulley, and means for effecting reciprocating movements of said rack.

9. A feeding device for metal working machines, said device including a gripper mounted for reciprocating movement and having means to grasp a piece of stock, means for reciprocating said gripper, a feed actuating disk, a member movable radially on said disk, means for adjustably securing said member in different positions, and a connection between said member and the reciprocating means for said gripper for reciprocating the latter.

10. A feeding device for metal working machines, said device including an endless, flexible actuator and said actuator including a gripper interposed in the length of said actuator, means on said gripper for grasping a piece of stock, a pulley to which said actuator is attached, a feed actuating disk, a member radially movable on said disk, means for securing said member in different positions on said disk, and a connection between said member and said pulley for oscillating the latter.

11. A feeding device for metal working machines, said feeding device including an

- endless, flexible actuator and said actuator including a gripper interposed in the length of said actuator, means for moving said actuator back and forth, means on said gripper
- 5 for grasping a piece of stock, a member for engaging said piece of stock for an operation thereon, and means for causing engagement of said member with said stock during a backward movement of said gripper.
- 10 12. A feeding device for metal working machines, said device including an endless, flexible actuator, and said actuator including a gripper interposed in the length of said actuator, means on said gripper for grasping
- 15 a piece of stock, means for imparting cycles of movement to said actuator, each cycle including a movement thereof back and forth, a member to effect an operation upon said stock during each cycle of movement of said
- 20 member, and means for synchronizing the cycles of movement of said member and of said actuator.
13. A feeding device for metal working machines, said device including an endless, flexible actuator and said actuator including a gripper interposed in the length of said actuator, means on said gripper for grasping a piece of stock, means for effecting cycles of movement of said actuator, each cycle comprising a movement thereof back and forth, means for changing the length of said cycle of movement, a member for performing an operation upon said stock during each cycle of movement of said member, and
- 35 means for synchronizing the cycles of movement of said actuator and of said member.
14. A feeding device for metal working machines, said device including an endless, flexible actuator and said actuator including a gripper interposed in the length of said actuator, means on said gripper for grasping a piece of stock, means for effecting cycles of movement of said actuator, each cycle including a movement back and forth thereof, means for changing the zone of movement of said gripper, a member for performing an operation upon said stock during each cycle of movement of said member, and means for synchronizing the cycles of movement of said actuator and of said member, irrespective of the degree of movement of said gripper.

GEORGE F. MATTESON.
